UNITED STATES PATENT OFFICE.

ANN DIXIE LANGDON, OF PIEDMONT, CALIFORNIA.

DESIGN FOR A DOLL.

Application filed September 4, 1923. Serial No. 7,145. Term of patent 7 years.

To all whom it may concern:

Be it known that I, ANN DIXIE LANGDON, a citizen of the United States, residing in Piedmont, county of Alameda, and State of California, have invented a new, original, and ornamental Design for Dolls, of which the following is a specification, reference being had to the accompanying drawing, forming part thereof.

The figure shows a perspective view of the doll.

I claim:

The ornamental design for a doll, as shown.

ANN DIXIE LANGDON,

Witnesses:

JOHN H. HERRING,
DOROTHY M. BALL.
